UNITED STATES PATENT OFFICE.

HARLEY D. PENNINGTON, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

COATING MACHINE.

Application filed January 20, 1922. Serial No. 530,505.

My invention relates to coating machines which may be used in galvanizing processes and other coating processes.

An important object of the present invention is to provide an improved coating machine in which the frame for supporting the rolls, guides and other parts is arranged to be entirely above the level of the coating fluid in the pot or vat, and in which the 10 housings for the intermediate or bottom rolls are made separate from and are detachably connected to the frame, whereby when the roll housings are destroyed by the corrosive action of the coating material, 15 they can be removed and new housings substituted without the necessity of providing a new frame.

Another object of the invention is to provide a novel construction of housings for the 20 intermediate or bottom rolls adapted to facilitate removal of these rolls from the frame.

A further object of the invention is to provide improved means for driving the 25 intermediate or bottom rolls adapted to facilitate removal of the rolls from the housings and enabling these rolls to be driven as their respective diameters decrease due to wear and frequent dressings, without 30 the necessity for changing the gears on the rolls.

Still another object of the invention is to provide a detachable driving connection between the driving means and the several 35 sets of rolls in the frame, whereby any of these sets of rolls may be readily disconnected from the driving means, or all of the rolls may be disconnected therefrom to permit raising of the frame for removal of the 40 rolls and other parts carried thereby from the vat for cleaning.

My invention will be better understood by reference to the following description taken in connection with the accompanying drawings showing one embodiment of my invention, and in which:

Figure 1 is a plan view of a machine embodying my invention.

Figure 2 is a section on line II-II of 50 Figure 1;

Figure 3 is a section on line III-III of Figure 1;

Figure 4 is a perspective view of the supporting frame;

Figure 5 is a partial section of a modification of my invention; and

Figures 6 and 7 show details of a coupling.

Referring to the drawings, the device is mounted on a suitable foundation structure 60 1, in which is placed the pot or vat 2 for containing the coating bath. The supporting frame is mounted on the end walls of the vat and comprises side members 3 and 4 (see Figure 4) joined together by rods 65 or other members 5. It will be seen that the supporting frame is so constructed and arranged as to be entirely above the level of the bath, and therefore no part of the frame is subjected to the corrosive action 70 of the bath. Housings 6 and 7 for the center rolls 8 and 9 are carried by the side members 3 and 4, respectively. The housings 6 and 7 are detachably connected to the members 3 and 4 by the portions 10 and 11 75 and are fastened together by the spacing rod 12.

The housing member 6 is considerably offset at 13 for a reason which will appear later. The housing member 7 is also offset 80 at 14 but is not as much as the member 6.

The intermediate or bottom rolls 8 and 9 are provided with bearing blocks 15 and 16. These bearing blocks 15 and 16 are grooved along their edges and slide upon the slides 17 and 18 of the housings 6 and 7 and are thereby guided and held in place.

The intermediate or bottom rolls 8 and 9 are provided with worm wheels 19 and 20. Meshing with the worm wheel 19 is a worm 90 21 and with the worm wheel 20 is a similar worm 22. These worms are carried on shafts which project upwardly and are carried at the top in a suitable frame structure 23, which is supported by the side frame member 4. At their upper ends these shafts are provided with worm wheels 24 which mesh with a worm 25 on the shaft 26, which is driven from the power motor 27 through suitable gears 28, 29 and 30. 95

It sometimes becomes necessary to adjust the worms 21 and 22 with respect to the gears 19 and 20. This is effected in the present instance by inserting wedge shaped members 67 behind the bearing blocks of the worms and providing a hand wheel 68 for moving the wedge members 67 up or down, depending upon whether the worm

is to be moved away from or closer to the worm gear. Any other suitable means may be provided for this adjustment.

The rolls 8 and 9 are held in proper contact by counterweighted arms 69, pivoted to the frame at 70 and acting upon the upper ends of vertically sliding rods which latter bear at their lower ends upon the bearing blocks 15.

10 By driving the rolls 8 and 9 independently in the manner above described, instead of gearing them directly together and driving one through the other, these rolls can be driven while maintaining surface contact between them, even after their diameters have become greatly reduced due to wear and frequent dressings, without the necessity for changing the gears 19 and 20.

15 The rolls 8 and 9 are grooved as shown in Figures 1 and 3. Guides 31 and 32 extend between the rolls 8 and 9 and are positioned in the grooves, as shown in these figures. The guides 31 and 32 perform the usual function of such guides and are supported at 25 their ends from the frame structure by any suitable means.

20 Mounted on the foundation structure is a pair of wringer rolls 34 of any desired construction. The rolls are held together by springs 34'. The compression on these springs may be changed by the adjusting screws 34''. A pair of intake rolls 33 is mounted upon the end of the frame and guides 35 and 36 guide the sheets or other 25 material from the rolls 34 to the rolls 33.

25 Mounted on the other end of the frame are the exit rolls. In the drawings two sets of exit rolls 37 and 38 are shown, but in many instances it is not necessary to provide two sets of such rolls and in which event the said rolls 38 may be dispensed with.

30 A counterweighted arm 39 pivoted at 40, bears against one of the exit rolls 37 and holds the same against the other roll of that pair with a force dependent upon the position of the counterweight 41. A guide member 42 directs the material out of the pot over a roller 43.

35 The motor 27 is arranged to operate all of the rolls of the machine. It operates the center rolls 8 and 9 through the medium of gears 28, 29 and 30 and the worms connected with the shaft 26. It operates the feed rolls through the gears 44 and 45, which latter gears connect with the shaft 46, which in turn is provided with a gear (not shown) which operates the feed rolls 33. The shaft 46 is also provided with a sprocket 47 which connects through a chain 48 with a sprocket 49 on the feed rolls 34.

40 The gears 44 operate the shaft 50, which has at one end thereof a bevel gear 51 meshing with a gear 52 on the shaft 53. On 45 one end of the shaft 53 is a sprocket 54

which is connected with a sprocket 55 by a chain 56. The sprocket 55 is mounted on the shaft 57 which shaft carries the roller 43.

45 The other end of the shaft 53 is provided with a plurality of gears 58 of different diameters. A shaft 59 is placed parallel to the shaft 53 and is adapted to carry a gear 60 which will be of suitable size to mesh with any one of the gears 58, depending upon the desired relative speeds of rotation 50 between the shafts 53 and 59. The shaft 59 is connected to a shaft 59^a which has on its other end a gear 61 which meshes with the gear 62 on the end of one of the exit rolls 37. The gear 61 also meshes with the gear 63 on the end of one of the exit rolls 38. The gear 61 also meshes with an idler gear 64, which in turn meshes with a gear 65 on the end of one of the exit rolls 37 and with a gear 66 on the end of one of the exit 55 rolls 38. The shafts 46, 26 and 59^a are provided with couplings 71. These couplings are shown in detail in Figures 6 and 7. The coupling comprises a member 72 which has been bored out to receive the reduced end 60 portion 73 of a shaft 74. The member 72 is provided with a key-way to receive a key 75 which also enters a key-way in the portion 73 of the shaft. A portion 76 of the member 72 extends beyond the end of the portion 73 and a slot 77 is cut through it as shown in Figures 6 and 7. A rectangular drive shaft 78 such as the shafts 46, 26 and 59^a is placed in the slot 77. A sleeve 79 is slipped over the portion 76 to retain the shaft 78 in the slot 77. A keeper 80 is placed in the coupling to hold the parts in place as clearly shown in Figures 6 and 7.

55 Figure 5 shows a modification of my machine. This modification provides means whereby smooth intermediate or bottom rolls 8^a and 9^a may be used. In that event the guides 31^a and 32^a terminate adjacent the rolls 8^a and 9^a and are supported by members 100 which are fastened to the supporting frame structure. In this structure the bearing blocks 15^a and 16^a are not provided with grooves, but have shoulders which bear upon the inside of the housings 6^a and 7^a as shown. In all other respects the arrangement shown in Figure 5 is the same as heretofore described, the corresponding parts being marked with the exponent "a."

60 In operation the sheets or other material to be treated are introduced to the wringer rolls 34 from which they pass to guides 35 and 36 and to the intake rolls 33 and from these rolls into the bath through the guides 31 and 32. As they pass through these guides they pass between the intermediate or bottom rolls 8 and 9 and from these rolls out to the exit rolls 37 and 38 and over the roller 43.

65 In some instances a sheet being treated

will stick in the guides, and it is desirable to be able to lift the upper roll 8 out of the machine quickly, so that the stuck sheet may be removed. The construction of the housings for the intermediate or bottom rolls so that their lower portions are spaced apart a less distance than the distance between the side members 3 and 4 of the supporting frame facilitates removal of the upper roll 8, as this can be done by merely swinging over the levers 69, and without first removing any other parts of the machine. With this construction, the top roll 8 may be removed and replaced again with very little delay in the operation of the machine, which is a decided advantage.

In the structure shown in Figure 5 the whole frame may be lifted from the pot and a bar used to raise the bearing blocks 15^a until they clear the roll 8^a, whereupon the roll 8^a may be taken out through the windows between the legs 17^a and 18^a of the housing.

The couplings 71 provide means whereby the driving motor 27 can be quickly disconnected from any set of the rolls in the supporting frame when it is desired to stop or to remove such rolls, or whereby the motor can be readily and quickly disconnected from all of said rolls when it is desired to raise the supporting frame to remove the rolls and other parts from the vat for cleaning. The shaft 57 is not provided with couplings, as that shaft is mounted in open bearings so that the roll 43 may be removed from the machine by lifting it out of the bearings.

It is desirable that the surface speed of the exit rolls should be kept at approximately a predetermined amount. These exit rolls after being used for awhile become pitted or otherwise roughened or misshapened on their surfaces. It is necessary to turn down these rolls at intervals to keep their surfaces in good condition. When this is done the diameter of the rolls is decreased; consequently it is necessary to rotate the rolls at correspondingly greater revolutions per minute in order to maintain surface speed at the desired amount. This is accomplished by the speed changing gears 58 and 60. When it is necessary to turn down the exit rolls an approximate amount will be turned off. This amount will be figured with relation to the speed change gears so as to give the desired surface speed to the rolls. This results in a longer life of the rolls.

An important advantage of the present invention arises from the construction and arrangement of the supporting frame so as to be entirely above the level of the bath, and from the provision of housings for the intermediate or bottom rolls which are formed separate from and detachably connected to the frame.

Another advantage of the invention arises from the construction of the housings for the intermediate or bottom rolls with their lower portions spaced a less distance apart than the side members of the supporting frame, whereby removal of the intermediate rolls is facilitated.

Another advantage of the invention arises from the particular arrangement of driving means for the intermediate rolls.

A further advantage of the invention arises from the provision of detachable driving connections between the driving motor and the driven rolls.

I claim:

1. In a coating machine, a receptacle for the coating bath, a supporting frame constructed and arranged to be wholly above the level of the bath, a pair of oppositely arranged roll housings detachably secured to said frame and depending into said receptacle, and a pair of rolls supported in said housings, substantially as described.

2. In a coating machine, a receptacle for the coating bath, a supporting frame constructed and arranged to be wholly above the level of the bath, a pair of oppositely arranged U-shaped roll housings detachably secured to said frame and depending into said receptacle, and a pair of rolls supported in said housings, substantially as described.

3. In a coating machine, a receptacle for the coating bath, a supporting frame constructed and arranged to be wholly above the level of the bath, a pair of oppositely arranged roll housings detachably secured to said frame and depending into said receptacle, and a pair of rolls supported in said housings and arranged one above the other, substantially as described.

4. In a coating machine, a receptacle for the coating bath, a supporting frame constructed and arranged to be wholly above the level of the bath, a pair of oppositely arranged roll housings detachably secured to said frame and depending into said receptacle, a pair of separate bearing blocks slidably supported in each of said housings one above the other, and a pair of rolls journaled at their ends in said bearing blocks, substantially as described.

5. In a coating machine, a receptacle for the coating bath, a supporting frame comprising two parallel rectilinear side members extending longitudinally of and resting at their ends upon the upper edges of the end walls of said receptacle, a pair of oppositely arranged roll housings detachably secured to said side members and depending into said receptacle, and a pair of rolls supported in said housings, substantially as described.

6. In a coating machine, a receptacle for the coating bath, a supporting frame comprising a pair of parallel side members ex-

- tending longitudinally of said receptacle and arranged to be wholly above the level of the bath, a pair of oppositely arranged U-shaped roll housings detachably secured to said side members, each of said housings having its lower portion offset toward the other housing, and a pair of rolls of less length than the distance between said side members supported in said housings, substantially as described. 5
7. In a coating machine, a receptacle for the coating bath, a supporting frame comprising a pair of side members extending longitudinally of said receptacle and arranged to be wholly above the level of the bath, a pair of oppositely arranged roll housings detachably secured to said side members intermediate the ends of the latter and depending into said receptacle, a pair of rolls supported in said housings, and a pair of exit rolls supported by said side members adjacent one end thereof, substantially as described. 10
8. In a coating machine, a receptacle for the coating bath, a supporting frame comprising a pair of side members extending longitudinally of said receptacle and arranged to be wholly above the level of the bath, a pair of oppositely arranged roll housings detachably secured to said side members intermediate the ends of the latter and depending into said receptacle, a pair of rolls supported in said housings, a pair of exit rolls supported by said side members adjacent one end thereof, and a pair of intake rolls supported by said side members adjacent the opposite end thereof, substantially as described. 15
9. In a coating machine, a frame, a pair of oppositely arranged roll housings supported by and depending from said frame, a pair of bearing blocks slidably arranged one above the other in each of said housings, a pair of rolls journaled at their ends in said bearing blocks, and means for driving each of said rolls independently of the other comprising a gear on one end of each of said rolls, a pair of shafts each having a driving connection at one end with the corresponding gear on one of said rolls, a gear on the opposite end of each of said shafts, and means for driving said last mentioned gears, substantially as described. 20
10. In a coating machine, a supporting frame, a pair of oppositely arranged roll housings supported by and depending from said frame, a pair of bearing blocks slidably arranged one above the other in each of said
- housings, a pair of rolls journaled at their ends in said bearing blocks, a gear on one end of one of said rolls and a gear on the corresponding end of the other of said rolls, a pair of vertical shafts one having a worm on its lower end meshing with the gear on one of said rolls and the other having a worm on its lower end meshing with the gear on the other of said rolls, adjustable means for maintaining said worms in engagement with said gears, and means for driving said shafts, substantially as described. 25
11. In a coating machine, a frame comprising parallel side members, a pair of oppositely arranged roll housings supported by and depending from said side members, said roll housings having their lower portions spaced a less distance apart than the distance between said side members, and a pair of rolls supported in said housings, substantially as described. 30
12. In a coating machine, a frame comprising parallel side members, a U-shaped housing depending from each of said side members, said housings being oppositely arranged and each having its lower portion offset toward the other housing, a pair of bearing blocks slidably arranged one above the other in said lower portion of each housing, a pair of rolls journaled at their ends in said bearing blocks, a weighted lever arranged above each of said upper bearing blocks and pivoted at one end to the frame, and pressure transmitting means intermediate each of said levers and its corresponding upper bearing block. 35
13. In a coating machine, a supporting frame, a roll supported by said frame, stationary means for driving said roll spaced from said frame, and a driving connection between said driving means and said roll comprising an elongated shaft extending between said driving means and roll and having each end thereof positioned in a slot in a coupling member, and a removable sleeve engaging each of said coupling members for maintaining the end of the shaft in the slot thereof, substantially as described. 40
14. The combination with a tinning machine having a driving means and finishing rolls driven thereby, of an adjustable variable speed gearing interposed between the driving means and the rolls. 45
- In testimony whereof I have hereunto set my hand. 50

HARLEY D. PENNINGTON.
